EXTRACTION DRIER

John T. Bian, Chicago, Ill., assignor to the partnership composed of John T. Bian, Anthony Zwissig, William J. Spellman, Burton H. Williams, Ernest Booth, and Thomas V. McDavitt

Application November 1, 1947, Serial No. 783,509

4 Claims. (Cl. 219—19)

1

This invention relates to a drier and more particularly to a drying means for drying a printed web of paper as it comes off a rotary press.

In the operation of modern high speed rotary presses, a web of paper is printed upon both sides and then passed immediately to a folding or cutting machine. In the folding or cutting operation sheets are piled one upon the other and difficulty has been experienced in that the wet ink on the paper tends to smudge. The methods employed for drying the ink generally consist of a line of gas flames over which the paper is passed rapidly and the ink "flash dried." Any maladjustment of the speed of the paper over the flame or the intensity of the flame, results in either poor drying of the ink or in overdrying, even to the extent of igniting the paper. In fact, fires are extremely common in press rooms.

I have invented and am herein disclosing and claiming a novel means and method for drying printed paper which comprises, broadly, passing the moving web through an open ended boxlike heating chamber and subjecting the web to radiant heat on both sides as it passes through the chamber.

The invention will be described as disclosed in the embodiment shown in the accompanying drawings in which Fig. 1 is a diagrammatic view of the drier and a portion of a rotary press. Fig. 2 is a vertical section through the drier and Fig. 3 is a horizontal section along line 3—3 of Fig. 2.

Referring now to the drawings, 10 indicates a drier through which a moving web of printed paper 11 is passed after coming from drums 12 and 13 of a rotary press. Guide rolls 14 and 15 at opposite ends of the drier 10 serve to align the web for its passage through the drier. Additional rollers 16, 17 and 18 conduct the dried web to a folding or cutting machine (not shown). The drier 10 is an open ended boxlike chamber having side walls 19 and top and bottom walls 20 and 21. The walls are insulated with suitable insulating material 22 whose interior side is covered with a reflecting means 23 such as tinfoil. The web 11 enters the drier through the open end 24 and leaves through the end 25 which is partially closed by an upstanding end wall 26 forming a pocket 27 immediately interior of the end wall.

Shortly after entering the entrance 24, the upper surface of the web is subjected to radiant heat from a first heater 28. The heater extends transversely across the entire chamber 10 and comprises a pair of spaced parallel electrical resistance elements 29 and 30. A copper screen 31 is attached to the heating elements 29 and 30

and conducts heat therefrom over the entire area of the screen and hence over the full width of the web. A second heating element 32 is located to the rear of the element 28 and positioned beneath the web to apply heat to the under side thereof. The second heating element comprises three electrical resistance elements 33, 34 and 35. The elements 33 and 34 are positioned relative to each other to form a V as shown while the third element, 35, is located adjacent the exit 25. A second copper screen 36 is connected to all three elements. The screen 36 has its front edge immediately beneath the rear edge of the heating element 30 so that it forms a radiant heat member in the shape shown, which is analogous to a truncated V. The various heating elements receive their energy through conduits 37 which are connected with a sixty ampere magnetic relay 38 in turn connected to a sixty ampere fused switch 39 and then by conduits 40 to a 230 volt line (not shown). A manually operable switch 41 is provided in the circuit.

If desired, the web exiting from the heating means may be air-wiped by means of the perforated pipe 42 connected by means of the pipe 43 to a source of compressed air.

In the installation made, the drier was positioned very close to the last rollers of the press, the distance from the entrance 24 to the rolls 12 and 13 being approximately 36 inches. The length of the chamber was 64 inches and its overall height 9 inches. The outside width of the chamber was 74 inches. The copper conducting screens together with the resistance elements were approximately one inch from the insulation 23. The copper screens were therefore approximately two and one-half inches from the web and were 16 gauge and one-half inch mesh. The temperature beneath the first heating element 28 was maintained at approximately 130° F. while the temperature at the center of the drier was held at 190° F. In the pocket 27 the temperature reached 230° F. The printed web travelled at a rate of 450 feet per minute and during its passage through the drier the ink was dried to a degree which permitted subsequent cutting and folding without smudging the ink. The temperatures may be varied somewhat with changes in the speed of the paper and the particular ink being dried.

An important and additional advantage of the use of my drier is that it eliminates practically all of the static electricity with which the paper has been charged during its passage through the press. Static electricity causes the printed web to stick during the cutting and folding operations

with the resulting offset of those operations. In actual experience my drier has eliminated about 75% of these errors. The temperatures employed are considerably below the flash point for either the paper or the ink and hence the danger of fire is completely eliminated. As no gas flames are used no carbon dioxide fumes or gas fumes are given off.

While I have shown and described my invention in its preferred embodiment, it is to be understood that it is capable of many modifications. Changes, therefore, in the construction and arrangement may be made without departing from the spirit and scope of the invention as disclosed in the appended claims.

Having described my invention, I claim:

1. A drying means for drying a moving printed web from a printing press comprising an open ended chamber through which the web passes, a first heated element within the chamber above the web and a second heated element within the chamber and below the web, said heated elements comprising foraminous members extending transversely across the path of the moving web, electrical heating members contacting said elements along their margins for heating the same and an upstanding end wall at the exit end of said chamber adapted to form a pocket of air having a higher temperature than the balance of air in the chamber adjacent said exit end, said web being unsupported during its passage through the chamber whereby both faces of the web are entirely exposed to radiant heat from said elements.

2. A drying means for drying ink on a moving printed continuous web from a printing press comprising a chamber having a top, a bottom, and sidewalls, and having open ends, means for passing the web through the chamber from end to end, a foraminous element in the chamber above the web, a second foraminous element in the chamber beneath the web, means for heating the marginal edges of the elements, said elements being heat conductors and each of said elements being wider than the web and extending across the chamber from side to side, said web being unsupported during its passage through the chamber whereby both faces of the web are entirely exposed to radiant heat from said elements.

3. A drying means for drying ink on a moving printed continuous web from a printing press comprising a chamber having a top, a bottom, and sidewalls, and having open ends, means for passing the web through the chamber, said web being substantially unsupported during its passage from end to end of the chamber, a metallic screen in the chamber above the web, a metallic screen in the chamber beneath the web, each of said screens being wider than the web and extending across the chamber from side to side and electrically heated members in contact only with the marginal edges of the screens for heating the screens by conduction of heat therefrom whereby both faces of the web are entirely exposed to radiant heat from said elements.

4. Apparatus of the character described in claim 3 in which said first screen is substantially rectangular in shape and said second screen is in the shape of a V, and in which said electrically heated members are in the form of relatively narrow strips contacting the marginal edges of the screens.

JOHN T. BIAN.
